UNITED STATES PATENT OFFICE.

MONROE GUETT, OF HARTFORD, CONNECTICUT.

DESIGN FOR A SWITCH-CONTACT.

SPECIFICATION forming part of Design No. 28,984, dated July 5, 1898.

Application filed May 23, 1898. Serial No. 681,514. Term of patent 14 years.

To all whom it may concern:

Be it known that I, MONROE GUETT, a citizen of the United States, residing at Hartford, county of Hartford, State of Connecticut, 5 have invented and produced a certain new and original Design for a Switch-Contact, of which the following is a full, clear, and exact description.

Figure 1 is a top plan view of my spring. 10 Fig. 2 is a side elevation thereof.

As shown in the drawings, the leading characteristics of my spring are a main portion doubled upon itself to form two leaves, which

leaves have upturned portions D and E, one of which leaves has also a curved slot F, a 15 circular portion C, a bridge G, and an opening H.

What I claim is—

The design for a switch - contact herein shown and described. 20

Signed at Hartford, Connecticut, this 20th day of May, 1898.

MONROE GUETT.
